CARD-HOLDING CLIP

Arthur Rex Jackson, London, England, assignor
to Remington Rand Inc., Buffalo, N. Y.

Application June 24, 1937, Serial No. 150,120

5 Claims. (Cl. 129—16.7)

This invention relates to visible card indexes and particularly to a card holding clip for use therein.

The invention comprehends the provision of a 5 clip for detachable mounting on a card holder adapted to cooperate with parts of the card holder in holding loose sliding sheets, split cards, split over-riding sheets and master cards, or any combinations of them, thereby facilitating the mounting and operation of loose sheets in a master visible index.

The invention further comprehends a clip formed of transparent flexible sheet material having portions formed for detachable cooperation with parts of conventional card holders so the clip may be readily attached to a card holder for slidably retaining one margin of a sheet or sheets against the card holder.

In the drawings:

20 Fig. 1 is a plan view of a conventional type of card holder supporting a record card and two additional sheets in front of the record card, the upper edges being retained by a clip made according to the invention and a portion of the 25 sheath on the card holder broken away to show the signalling feature.

Fig. 2 is a vertical cross section taken on line 2—2 of Fig. 1.

Fig. 3 is a fragmentary cross section taken on 30 line 3—3 of Fig. 1.

Fig. 4 shows the card holding clip in perspective.

Fig. 5 is a fragmentary plan view showing the lower visible margin of one of the added record 35 sheets illustrated in Fig. 1.

Fig. 6 is a view similar to Fig. 5 of the other added record sheet illustrated in Fig. 1.

Fig. 7 is a plan view of a conventional card holder similar to Fig. 1 with portions broken 40 away and shown in section to illustrate the clip attached to the card holder and the signalling feature obtained on the visible margin, a pair of over-riding sheets being applied to the record card and held in position by the clip in end to end relation, portions of one of the over-riding 45 sheets and the record card being shown bent forwardly out of normal position to more clearly illustrate details of construction.

Fig. 8 is a cross section taken on line 8—8 of 50 Fig. 7.

Fig. 9 is a cross section taken on line 9—9 of Fig. 7.

Fig. 10 is a cross section taken on line 10—10 of Fig. 7.

Fig. 11 is a fragmentary view of the added 55

record sheet shown in Fig. 7 illustrating the signalling means provided on the lower visible margin.

The conventional card holder illustrated has a sheet 1 formed with a row of perforations 2 providing a hinge. The marginal portion adjacent the hinge is stapled to a suitable supporting lug 3 used for detachably mounting the card holder in a suitable index tray or panel in a manner well known in the art. The opposite margin of card 10 holder 1 has a sheath 4 embracing the marginal portion thereof and suitably secured thereto by staples 5 in a manner now well known. Card holding sheet 1 is formed with a plurality of diagonal slots 6 to receive the corners of record 15 cards or sheets mounted on the card holders on the margin opposite to that engaged and supported in sheath 4. Sheet 1 is also formed with an elongated slot 7 originally formed therein to cooperate with positioning means and sheet feeding devices during the manufacture of the card holder in a manner well known to those skilled in the art.

The present invention uses slot 7 as a means for detachably receiving clip 8 in its support on 25 the card holder as shown in Fig. 1.

Clip 8 is formed of sheet material of any suitable character, transparent Celluloid being well adapted to the formation of the clip. Each clip 30 8 has a flat back section 9 and an extension on the upper side edge folded to form a return bend 35 providing a spaced guide flange 10. The ends of section 9 are formed with extensions 11 projecting in opposite directions and forming securing tongues adapted to extend through slot 7 at opposite ends thereof for engaging the opposite sides of the card holder from that engaged by back section 9. This inter-engagement of 40 tongues 11 through slot 7 is clearly illustrated in Figs. 1 and 3, showing how the clip is supported on 45 the card holder. Since sheet Celluloid is highly flexible material, it will be appreciated that section 9 is flexed to shorten the distance between the ends of projections 11 sufficiently, to be less than the length of slot 7 whereupon tongues 11 may be inserted through slot 7 and then released to allow section 9 to resume its normal flat relation and thereby interlock with the card holder to secure the clip in position.

Clip 8 is mounted on card holder sheet 1 in the 50 position shown in Fig. 1 so that guide flange 10 projects toward sheath 4 on the free margin of the card holder.

A record card 12 of the size to fill the card holder is shown in Figs. 1 and 2 with its lower 55

margin folded to provide a forwardly and upwardly extending marginal strip 13. The fold portion including the lower margin of the card and strip 13 are inserted in sheath 4, with marginal portion 13 formed with suitable index indicia that will be displayed through the transparent sheath when the card holder illustrated is associated with similar card holders in visible indexed relation. Marginal strip 13 is provided at 14 with an opening adjacent the fold portion to display a signal on another record card or sheath inserted in the rear of marginal strip 13. The upper edge of card 12 is engaged under flange 10 of clip 8 by flexing the card to shorten the distance between the upper and lower margins to less than that between the sheath and clip 8, whereupon the upper edge of the card is engaged under flange 10 and subsequently held close to the face of sheet 1 of the card holder. In the use of this clip 8 it is not necessary to use the conventional diagonal slots 6 for retaining record cards on the card holder.

In Figs. 1 to 3 two additional record cards or sheets 15 and 16 respectively, are shown superposed on record card 12 with one margin engaged in sheath 4 between record card 12 and folded marginal portion 13 thereon, while the opposite margins of cards 15 and 16 are engaged under flange 10 of clip 8 in a slidably manner so that either record member 15 or 16 which is of less width than the card holder may be slidably moved back and forth across the card holder. The free marginal portion of the uppermost record member 16 is displayed through opening 14.

Record members 16 and 15 respectively, are shown in Figs. 5 and 6, respectively. Fig. 5 shows the visible marginal portion of record member 16 illustrating the ruled areas 17 and 18 on the margin thereof adapted to provide a signal for display through opening 14. Any other signalling means such as colored areas or other well known devices may be applied to the margin of either of record sheets 15 and 16 so they will be displayed through aperture 14.

It will be seen that with these two added record sheets 15 and 16 they can be moved back and forth across the card holder in order to be adapted for use in any one of a series of different applications in keeping records. This slidable mounting of the sheets and their retention by clip 8 provides features of construction that will facilitate additional uses for visible card records including signalling features, in addition to the signal indicating whether a particular card may or may not be out of the file, thereby increasing the amount of information signalled on the visible margin of each card holder, without unduly increasing the amount of build-up in the card holders through the addition of extra sheets.

Fig. 6 shows card 15 with a different type of signal area 20 on the visible margin thereof. It will be seen from a comparison of Figs. 5 and 6 that either sheet 15 or 16 may be used as the top sheet in the record assembly so its signal area may be displayed through opening 14.

In Figs. 7 to 11 the card holder is constructed in the same manner as above described having sheet 1 provided with supporting lug 3 and sheath 4 on the visible margin thereof. Clip 8 is mounted in slot 7 as above described, and a pair of record cards 21 arranged in edge to edge relation have one margin engaged in sheath 4 and adjacent portions of the opposite margin engaged under guide flange 10 of clip 8, a free upturned marginal strip portion 22 on the visible edge of

each card 21 being engaged over the front face of card 21 and in the sheath as illustrated in Figs. 7 and 8. Marginal strip 22 is provided with a signal aperture 23 in the marginal portion under transparent sheath 4.

A pair of over-riding sheets 24 of approximately equal width to record cards 21 are arranged in edge to edge relation over the face of cards 21 as illustrated in Figs. 7 and 8 and are provided with fold sections 25 that are engaged around the upper margin of record cards 21 in the manner shown in Fig. 7. It will be seen that the inner upper corners of these over-riding sheets are engaged under guide flange 10 of clip 8 which holds them in position on the record card.

A slidable sheet 26 is inserted over the faces of record cards 21 with one margin engaged between the record cards and marginal strips 22 while the opposite marginal portion of sheet 26 is slidably engaged under over-riding sheet 24 and under guide flange 10 of clip 8. Record card or sheet 26 may be slidably moved back and forth over the face of record cards 21 and as shown in Fig. 11 may have signalling portions 27 and 28 for exposure through signal opening 23 to display the desired signal according to the signalling system to be used in the particular record to which this structure is applied.

It will thus be seen that where over-riding cards or sheets facilitate the indexing or keeping of record information in a file, the structure shown in Fig. 7 provides for the support of a pair of over-riding sheets that can be readily detached from the record by flexing the sheet with record cards 21, outwardly from engagement under flange 10 of clip 8, and then, removing the desired sheet from the record card and replacing it with another if necessary. The signalling feature of the extra card or sheet 26 is also advantageous in that it facilitates the operation of the record for conveying in a visible index, more information than merely the index information on the marginal indexing strip.

It will, of course, be understood that a clip 8 may be used in any conventional card holder of the character shown where it is provided with a slot similar to slot 7 or suitable equivalent means with which the clip may be detachably connected, and that in some types of records numerous card holders may not require the use of a clip and extra sheet or sheets, and in such cases the clip can obviously be omitted and the card holder used in its conventional manner.

The invention claimed is:

1. In a visible index, a card holder having an inwardly facing flange on one margin, for slidably receiving a card margin under said flange, the portion of said card holder opposite said margin having an opening, and a clip having portions interengaged with said card holder through said opening detachably mounting said clip on said card holder, and a guide flange on said clip facing toward the first-mentioned flange in spaced parallel relation to said card holder for slidably receiving the opposite margin of said card.

2. In a visible index, a card holder having a transparent sheath on a free margin thereof and formed with an aperture at the side opposite 70 said margin, a clip formed of sheet material folded upon itself to provide a base portion and a spaced parallel flange, and projections on said base portion for engaging through said aperture to detachably mount said clip on said card hold- 75

er with said flange facing said sheath for co-operation therewith to slidably receive opposite margins of cards for supporting them on said card holder for lateral sliding movement.

- 5 3. In a visible index, a card holder formed of a sheet having a transparent sheath embracing one marginal portion and a slot in the opposite portion of said sheet parallel to said sheath, and a clip formed of transparent sheet material having a base section formed with a return bend portion on one margin overlying said base in spaced parallel relation thereto, and projections on said base, said projections engaging through said slot to overlie the opposite face of said sheet from said base section for detachably mounting said clip on said card holder with said flange extending toward said sheath for cooperation therewith to slidably receive opposite margins of a card for sliding movement of said card laterally over said card holder.
- 10 4. In a visible index, a card holder formed of a sheet having a transparent sheath embracing the free marginal portion thereof and an elongated aperture in the opposite portion, and a clip formed of flexible sheet material formed with oppositely directed attaching tongues projectable through said aperture by flexing said clip to shorten the distance between the ends of said aperture, said clip having an offset flange formed
- 15
- 16
- 20
- 25
- 30

thereon extending toward said sheath, whereby a card may be mounted on said card holder for lateral sliding movement with opposite margins slidably engaged under the flange on said clip and in said sheath.

- 5 5. In a visible index, a card holder formed of a sheet having a transparent sheath embracing the free marginal portion thereof and an elongated aperture in the opposite central portion, a clip formed of flexible sheet material having 10 oppositely directed attaching tongues projectable through said aperture by flexing said clip to shorten the distance between the ends of said tongues to less than the length of said aperture, said clip having an offset flange formed thereon 15 extending toward said sheath, a pair of adjacent cards mounted on said card holder having opposite marginal portions engaged under said flange of said clip and in said sheath respectively, and a pair of folded sheets shorter than 20 the distance between said sheath and clip mounted in end to end relation having fold portions embracing the margin of said cards engaged under said clip with adjacent ends of said folded sheets at the folds engaged under the 25 flange on said clip, whereby said clip retains said folded sheets in attached position on the margins of said cards.

ARTHUR REX JACKSON. 30
